(57) **CLAIM**

I claim the ornamental design for a coffee press, as shown.

DESCRIPTION

FIG. 1 is a top orthographic view of a coffee press, showing my new design.

FIG. 2 is a front orthographic view thereof, the rear being a mirror image of the same.

FIG. 3 is a bottom orthographic view thereof; and,

FIG. 4 is a front section view thereof, taken along the lines of 4-4 of FIG. 1.

The broken lines show environmental subject matter that forms no part of the claimed design.
